DISPLAY CARTON

Kenneth Van Dyck, Westport, Conn., assignor to The Lionel Corporation, New York, N.Y., a corporation of New York

Filed May 29, 1961, Ser. No. 65,393

Term of patent 14 years

(Cl. D58—12)

FIG. 1 is a front perspective view of a display carton showing my new design;

FIG. 2 is a front elevational view thereof; and,

FIG. 3 is a top plan view thereof.

A view of the rear and the side not shown in the drawing would be substantially the same as the front and side as shown.

I claim:

The ornamental design for a display carton substantially as shown and described.
